United States Patent Office.

T. S. SMITH, OF NEW HAVEN, CONNECTICUT.

Letters Patent No. 71,546, dated November 26, 1867.

IMPROVED BALL CASTER.

The Schedule referred to in these Letters Patent and making part of the same.

TO ALL WHOM IT MAY CONCERN:

Be it known that I, T. S. SMITH, of New Haven, in the county of New Haven, and State of Connecticut, have invented a new Improvement in Ball Casters; and I do hereby declare the following, when taken in connection with the accompanying drawings, and the letters of reference marked thereon, to be a full, clear, and exact description of the same, and which said drawings constitute part of this specification, and represent, in—

Figure 1, a side view

Figure 2 a central section, and in

Figure 3 an under side view of the ball-seat.

This invention relates to an improvement in casters for furniture, and consists in the peculiar formation of the seat combined with the ball, whereby the driving-point is far above the centre, and near the point of bearing.

Ball casters of various forms have been constructed, but generally so great has been the friction, that when attached to heavy articles the ball would not revolve, but in all such, the point of driving the ball, that is, the point which bears against the ball in the movement of the furniture, is so far below the centre and distant from the point of bearing, that the leverage from the point of bearing to the point of driving and point of contact with the floor is so great that the ball will not revolve.

By my invention these difficulties are entirely overcome, and in order to the better understanding of my invention, as well as to enable others to construct the same, I will proceed to a description thereof. As illustrated in the accompanying drawings—

A is the upper part or seat of the caster, formed with a recess, B, having straight sides, as seen in fig. 3. These may be three or four; I prefer four. The bottom of this recess is flat, so that the ball C will bear against the surface of the recess with the least possible friction, and when so bearing, the sides of the recess are of such dimensions that, when bearing upon one side, the ball will not quite touch the opposite side. Thus, when the seat A is fixed to the furniture, and the ball C placed in the recess thereunder, the weight is supported upon the ball upon a single point, and when the furniture is moved, say to the left, the point *a* of one side of the recess bears against the ball near the top, so that the leverage from the ordinary construction is reversed, and the longer arm of the lever being toward the floor, upon which is the greater amount of friction, and thus the ball will be driven, revolving upon the point of contact upon the surface of the recess B. In order to prevent the ball from dropping from its seat, when the furniture is raised, I form a cup, D, which wholly or partially surrounds the ball below its centre, but so as not to touch the ball when the weight of the furniture rests upon the ball. This cup is attached to the seat in any convenient manner, so that, when the furniture is raised, the ball will drop into the cup, and be held in position to return to its seat when the furniture is again set down.

I do not broadly claim a ball caster, as such are common and well known; but

What I do claim as new and useful, and desire to secure by Letters Patent, is—

The seat A, constructed with a recess, B, so as to form an angular recess, said recess forming a single bearing-point on the top, and two driving-points *a* near the top of the ball, as set forth.

T. S. SMITH.
